(57) **CLAIM**

The ornamental design for a electrical adaptor, as shown and described.

DESCRIPTION

FIG. 1 is an isometric front view of a first embodiment of my new design for an electrical adaptor;

FIG. 2 is an isometric rear view thereof;

FIG. 3 is a front view thereof;

FIG. 4 is a rear view thereof;

FIG. 5 is a left side view of FIG. 3;

FIG. 6 is a right side view of FIG. 3;

FIG. 7 is a top view of FIG. 3;

FIG. 8 is a bottom view of FIG. 3;

FIG. 9 is an isometric front view of a second embodiment of my new design for an electrical adaptor;

FIG. 10 is an isometric rear view thereof;

FIG. 11 is a front view thereof;

FIG. 12 is a rear view thereof;

FIG. 13 is a left side view of FIG. 11;

FIG. 14 is a right side view of FIG. 11;

FIG. 15 is a top view of FIG. 11; and,

FIG. 16 is a bottom view of FIG. 11.
